VARIABLE PITCH AND REVERSING PRO-
PELLER FOR MARINE MOTORSLeRoy M. Melius, Southport, Conn., assignor to
The Lemel Corporation, Bridgeport, Conn., a
corporation of Connecticut

Application May 7, 1947, Serial No. 746,538

3 Claims. (Cl. 170—135.7)

1

The present invention relates to a variable pitch and reversing propeller for marine motors, and has for an object to provide a device of this character especially adapted for cooperative association with an outboard type of marine motor. It is particularly proposed to provide a propeller assembly capable of convenient attachment as a unit to the outboard motor structure, such unit including the pitch changing mechanism, a propeller drive shaft and a drive gear, the latter adapted upon attachment of the unit to the conventional gear box portion of the outboard motor structure to engage within the gear box in meshing relation with the conventional driving pinion of the outboard motor. A further object is to provide manual control means for varying the propeller pitch, such control means being carried by the propeller unit and adapted for mounting upon a conveniently accessible part of the outboard motor structure.

A further object is to provide an improved propeller blade structure wherein a trailing blade portion of the blade is fixed to the propeller hub while a main body portion of the blade is pivotally mounted to vary its pitch, the fixed trailing blade portion being so disposed that it is in register with the main body portion in the full forward driving position of the blade, constituting an abutment to positively limit the driving position of the blade under the force of the pressure exerted upon the blade as it moves in the water, thus relieving the pitch changing mechanism of strain in the full driving position of the blade.

Other objects are to provide a propeller unit of simple, inexpensive and sturdy construction, and in which the working parts are effectually protected against damage from foreign objects coming into contact therewith.

With the above and other objects in view, an embodiment of the invention is shown in the accompanying drawings, and this embodiment will be hereinafter more fully described with reference thereto, and the invention will be finally pointed out in the claims.

In the drawings—

Fig. 1 is a side elevation of the lower end portion of an outboard motor provided with a propeller unit according to the invention.

Fig. 2 is a view, partially in end elevation and partially in vertical section, taken along the line 2—2 of Fig. 1.

Fig. 3 is a horizontal sectional view, taken along the line 3—3 of Fig. 1.

Fig. 4 is a vertical sectional view, taken along the line 4—4 of Fig. 3.

2

Fig. 5 is a vertical sectional view, taken along the line 5—5 of Fig. 3.

Fig. 6 is a vertical sectional view, taken along the line 6—6 of Fig. 3.

5 Similar reference characters indicate corresponding parts throughout the several figures of the drawings.

Referring to the drawings, the outboard motor, partially illustrated in the drawings, is of conventional type, being provided at its lower portion with the usual propeller mounting part including a horizontal fin portion 10 and a downwardly extending rudder portion 11, the latter being provided with a hollow suitably shaped gear box portion 12 in which is disposed the driving pinion 13 provided upon the lower end of the vertical shaft 14 extending downwardly from the engine. The gear box portion 12 is provided at its rearward open end with a recessed pocket 15 in 10 which there is normally engaged a cover and bearing plate which carries the conventional propeller shaft. It is proposed, according to the invention, to utilize this pocket to mount the variable pitch propeller unit of the invention.

25 The variable pitch propeller unit comprises a bearing fixture 16 of circular form adapted to fit in the recess 15 in sealing engagement with the open end of the gear box, being fixedly secured by bolts 17—17 disposed in counter-sunk holes 18—18

30 in the fixture and engaging screw holes 19—19 provided in the rearward face of the gear box for attaching the conventional cover and bearing plate thereto. The fixture 16 is provided with a central rearwardly projecting hub 20, and with an axial bore 21, in which the propeller drive shaft 22 is rotatably engaged, this drive shaft having bearing at its inner end in the bearing 23 provided in the gear box for the conventional propeller shaft, and adapted to have the rotatable

35 hub of the propeller secured upon its outer end, as will presently more fully appear. Upon the shaft there is secured a beveled gear 24 having its hub portion engaged in a counter-bore 25 of the bore 21, this gear being of suitable size and

40 type to mesh with the driving pinion 13 of the outboard motor. The fixture 16 is provided at its periphery with a circular flange 26 and a cylindrical bearing surface 27 which constitute bearing surfaces for the rotatable hub of the propeller, as

45 will presently more fully appear.

The propeller hub 28 is of cup-like form, and is provided at its outer end with a bushing 29 rigidly cast or otherwise secured therein in which the outer end of the shaft 22 is engaged and secured

50 by means of a shear pin 30. The hub is of gen-

erally cylindrical shape, and includes a cylindrical pocket 31 having bearing engagement at the forward open end of the hub with the flange 26 and bearing surface 27 of the fixture 16, this pocket providing a housing space for parts of the pitch changing mechanism. A pocket 32 of substantially rectangular form extends from the base of the circular pocket 31 and also provides housing space for parts of the pitch changing mechanism. At two opposed sides of the pocket 32 there are provided axially aligned diametrically disposed holes 33—33 having bearing sleeves 34—34 respectively secured therein, and in which are engaged the hub portions 35—35 of the propeller blades 36—36, the hub portions each having a shoulder 37 at its outer end which seats upon the outer end of the bearing sleeve in a pocket formation 38 at the outer end of the hole 33.

Upon the inner end of each propeller hub there is provided a stud 39, of square or other suitable non-circular form, engaged by a correspondingly shaped hole 40 in the base 41 of a lever 42, this lever being bent at an inclined angle from its base and provided with a link attaching end parallel to the base and disposed for swinging movement in the central diametric plane of the pocket 32. The base of the lever is secured to the propeller hub by a screw 43, the head of which extends beyond the stud 39 sufficiently to retain the lever thereon, the base of the lever being preferably of circular form and extending beyond the periphery of the propeller hub, so that it abuts the inner end of the bearing sleeve 33 and thus retains the propeller hub against axial movement. As clearly seen in Fig. 2, the levers of the opposed propellers are disposed in the pocket 32 at opposite sides of the propeller shaft.

Upon the hub 22 of the fixture 16 there is slidably engaged a flanged collar 44 fixed against rotation by means of a key 45 engaged in a key slot 46 in the hub. The collar is rotatably engaged by a ring 47, retained thereon by means of a plate 48 secured to the end of the collar by screws 49, this ring being provided at diametrically opposed points with forked extensions 50—50 to which links 51—51 are connected at one end by pivot pins 52—52, their other ends being connected by pivot pins 53—53 to the levers 42—42 of the propellers.

The collar 44 is provided with a forked extension 54 pivotally connected by a link 55 to the end of a lever 56 disposed for swinging movement in a pocket 57 provided in the fixture 16, the hub 58 of the lever being secured upon a vertical shaft 59 having bearing in a vertical passage 60 in the fixture. This shaft is secured against axial movement by a flange 61 rotatably engaged in a recess 62 of the upper end of the passage 60, and by a collar 63 secured upon its lower end by means of a nut 64 and rotatably disposed in a recess 65 at the lower end of the passage 60.

The shaft extends upwardly above the water line at one side of the outboard motor structure, and at its upper end is provided with suitable means for rotating it for the purpose of actuating the propeller shifting mechanism. For example, this actuating means may consist of a handle 66, pivotally mounted upon the upper end of the shaft by a pivot pin 67, and provided with a suitable pin 68 adapted to be engaged in one of a series of holes 69 provided in a bracket 70 secured to the outboard motor structure by screws 71. The holes 69 are so placed as to fix the position of the shaft when the propeller blades

are in any one of a series of predetermined positions of adjustment.

Each of the propeller blades 36 is provided with a fixed trailing blade section 72 rigidly connected to the hub 28 in any suitable manner. It may, for instance, be integrally cast thereon, welded thereto, or connected by screws or the like. The lead section 72 is provided with an abutment flange 73 which engages in flush relation in a recess 74 provided in the forward edge of the main body of the blade to limit the position of the blade in the full forward driving position of the propeller. The lead edge of the propeller is so generated that it extends continuously along the trailing blade section 72 and the main body of the blade.

The operation is as follows. As shown in Figs. 1 to 3, the propeller is in its position of adjustment for full forward speed, the actuating mechanism being retained in this position through locking the control handle 66 by engaging the pin 68 in one of the holes 69. In this position the main body portions 36 of the propeller blades are aligned with the lead sections 72 so that a maximum propelling surface is provided, and the pressure of water upon the blades is in a direction to maintain the edge of the blade in abutting relation against the lead section, thus relieving the pitch changing mechanism from excessive strain. The fixed relation of the lead section with the hub also prevents weeds and the like from becoming entangled between the lower edge of the movable blades and the hub.

In order to change the pitch to drive in reverse direction, the control handle 66 is moved to the selected location on the bracket 70, causing the shaft 59 to be rotated and swinging the lever 56 in clockwise direction, as seen in Fig. 3, causing the collar 44 to be shifted rearwardly upon the hub 20 and thereby swinging the levers 42 to rotate the blades into reverse driving position. In the reverse driving position the trailing blade sections 72 produce a slight counter effect, thus permitting the propeller to rotate at high speed while propelling the craft at a reduced speed, which is highly desirable in moving in reverse direction. At intermediate points of adjustment the blades will propel the craft forwardly or rearwardly at reduced speeds, and at an intermediate neutral point will cause the blades to rotate without propelling the craft.

I have illustrated and described a preferred and satisfactory embodiment of the invention, but it will be understood that changes may be made therein within the spirit and scope thereof, as defined in the appended claims.

What is claimed is:

1. For attachment to an outboard motor, wherein the motor includes a transversely relatively thin fin-like rudder portion at its lower end having a laterally extended hollow gear box portion opening at its rearward end and having a bearing fixture mounting portion surrounding said opening, a variable pitch and reversible propeller unit for external attachment to said motor comprising a cover and bearing fixture adapted to be secured upon said fixture mounting portion to close said gear box opening and having a shaft bearing coaxial with the longitudinal axis of said gear box and a hub bearing concentric to said shaft bearing, exteriorly accessible fastening means engageable with said fixture mounting portion to secure said fixture thereto, a propeller shaft journaled in said shaft bearing and extended forwardly therefrom for engagement in

said gear box and rearwardly therefrom for mounting a propeller hub, a hollow propeller hub fixedly mounted upon said rearwardly extended end of said shaft and having a bearing skirt portion in rotatable engagement with said hub bearing, propeller blades pivotally carried by said propeller hub, pitch changing means within said hub and operatively connected to said blades to pivotally move them, said fixture having a lever receiving recess between said propeller shaft and said hub bearing and a control rod bearing outwardly at one side of said shaft with its axis in a line outwardly spaced from and clear of said fin-like rudder portion, a control rod engaged in said rod bearing and extended upwardly therefrom exteriorly of and in outwardly spaced relation to said rudder portion, and a lever within said recess secured at one end upon said rod for swinging movement within said recess and operatively connected at its other end to said pitch changing means.

2. In a variable pitch and reversible propeller, a shaft, a propeller hub fixed to said shaft and having an internal recess surrounding said shaft, said propeller hub having propeller bearing openings extending from its outer surface to said internal recess, propeller blades pivotally mounted in said bearing openings and adapted to be pivotally adjusted by pitch changing means within said internal recess, and a trailing blade member fixed to said hub in relation to each of said propeller blades and arranged to be aligned there-

with in one position of pivotal adjustment of said propeller blades.

3. In a variable pitch and reversible propeller, a shaft, a propeller hub fixed to said shaft and having an internal recess surrounding said shaft, said propeller hub having propeller bearing openings extending from its outer surface to said internal recess, propeller blades pivotally mounted in said bearing openings and adapted to be pivotally adjusted by pitch changing means within said internal recess, and a trailing blade member fixed to said hub in relation to each of said propeller blades and arranged to be abutted thereby in one limit position of pivotal adjustment of said blades.
